United States Patent Office

Des. 224,677
Patented Aug. 29, 1972

224,677

WRENCH

John A. Lehnhard, Oak Brook, Ill., assignor to Sears,
Roebuck and Co., Chicago, Ill.

Filed Dec. 14, 1970, Ser. No. 26,492

Term of patent 14 years

Int. Cl. D8—05

U.S. Cl. D8—28

FIG. 2

FIG. 3

FIG. 4

FIG. 5

FIG. 6

FIG. 7

FIG. 8

FIG. 9

FIG. 1 is a top plan view of a wrench showing my new design;

FIG. 2 is a bottom plan view thereof;

FIGS. 3 and 4 are opposite side elevational views thereof;

FIG. 5 is a transverse cross-sectional view, on an enlarged scale, taken substantially on line 5—5 of FIG. 1;

FIG. 6 is a transverse cross-sectional view, on an enlarged scale, taken substantially on line 6—6 of FIG. 1;

FIG. 7 is a transverse cross-sectional view, on an enlarged scale, taken substantially on line 7—7 of FIG. 1;

FIG. 8 is a transverse cross-sectional view, on an enlarged scale, taken substantially on line 8—8 of FIG. 1, and

FIG. 9 is a transverse cross-sectional view, on an enlarged scale, taken substantially on line 9—9 of FIG. 1.

I claim:

The ornamental design for a wrench, as shown and described.
